UNITED STATES PATENT OFFICE

113,747

DESIGN FOR AN ALPHABET FOR FORMING MONOGRAMS

Arthur E. Knight, Jr., Providence, R. I., assignor
to Coro-Gram Inc., New York, N. Y.

Application February 11, 1939, Serial No. 82,931

Term of patent 3½ years

To all whom it may concern:

Be it known that I, Arthur E. Knight, Jr., a citizen of the United States of America, residing in Providence, county of Providence, and State of Rhode Island, have invented a new, original, and ornamental Design for Alphabet for Forming Monograms, of which the following is a specification, reference being had to the accompanying drawing, forming part thereof.

Fig. 1 is a plan view of an alphabet for forming monograms, showing my new design.

Fig. 2 is a perspective view of one of the initials in the alphabet.

I claim:

The ornamental design for an alphabet for forming monograms, substantially as shown.

ARTHUR E. KNIGHT, JR.
